UNITED STATES PATENT OFFICE.

MAURICE FIGOUR, OF PARIS, FRANCE, ASSIGNOR TO ETABLISSEMENTS CONTINSOUZA,
SOCIETE ANONYME, OF PARIS, FRANCE, A CORPORATION OF FRANCE.

CINEMATOGRAPHIC APPARATUS.

1,325,283.

Specification of Letters Patent. Patented Dec. 16, 1919.

Application filed January 7, 1919. Serial No. 270,014.

To all whom it may concern:

Be it known that I, MAURICE FIGOUR, citizen of the French Republic, residing at Paris, Department of the Seine, in France, and whose post-office address is 80 Rue de Charolais, in the said city, have invented certain new and useful Improvements in Cinematographic Apparatus; and I do hereby declare the following to be a full, clear, and 10 exact description of the invention, such as will enable others skilled in the art to which it appertains to make and use the same.

The rapidity with which films pass through projecting lanterns, prevents the 15 films from being damaged by the intense heat which is always developed at the luminous focus. If the film is stopped in order to fix on the screen for a certain length of time one picture of the series, the corresponding region of the film is very often 20 spoiled by the buckling or warping occasioned by an excessive rise in temperature and it may even happen that the film catches fire.

25 When cinematographic projections are being used for certain purposes, and particularly for exhibitions that are now so common for educational purposes, it is necessary to be able to stop the progress of the 30 film at certain pictures calling for detailed explanation.

The object of the present invention is to enable films to be utilized in this way with as many stoppages as may be desired during 35 exhibition by cooling the stopped film by means of an air current so as to protect it from any excessive rise in temperature.

By way of example, reference is made to the accompanying drawing in which the 40 cinematographic apparatus, seen from the front, is illustrated diagrammatically.

At 1 there is the aperture through which the pictures are projected on to the screen and behind this aperture the film 2 moves. 45 On the driving shaft, which is here assumed to be actuated by means of a crank, two oppositely directed ratchet wheels 4 and 5 are keyed, which gear with two toothed wheels 6 and 7 loose on the shaft 3. The wheel 50 6 drives the mechanisms that are usual in cinematographic apparatus and is itself driven by the ratchet 4 when the crank and its shaft rotate in the normal direction of the projection of the band for animated 55 photographs that is to say, clockwise.

The wheel 7, driving by means of the

pinion 8 a fan 9 that blows air through the piping 10 on to the film 2 through the aperture 1, is driven by the ratchet 5 when the shaft 3 is rotated in an anti-clockwise direction. 60

If desired, the fan may be arranged to operate under all circumstances, whether the pictures are fixed or animated. All that is necessary for that purpose is to add to the 65 fan drive, a pinion for reversing the direction of rotation.

When the operator wishes to change from animated projection to fixed projection, all that is required is to turn the crank in the 70 opposite direction and at the same speed. An automatic shutter protects the film by hiding the light during any stoppage or excessive slackening of the movement of the crank. This shutter, however, is always 75 objectionable.

When the apparatus is driven by a motor, the fan may be keyed to the shaft of the motor itself or driven by means of any mechanical connection, a suitably placed 80 clutch enabling air to be blown in during the stoppage of the cinematographic apparatus.

The accessory devices can obviously be modified without departing from the principle of the invention, the essential characteristic of which consists in the combination of the film-driving mechanism with a fan that acts when stoppage occurs in such a way as to protect the film against fire for 85 fixed projection. 90

I claim:

1. In a cinematographic apparatus, the combination with a shaft and a draft producing device, of means actuated by the shaft upon its rotation in one direction, only, for operating the draft producing device, and a power transmitting element actuated by the shaft upon its rotation in the opposite direction, only.

2. In a cinematographic projecting apparatus, the combination with a shaft of a rotary fan having a pinion on the shaft thereof, a gear carried by the shaft and meshing with said pinion, means for locking said gear to the shaft for rotation in one direction only, a reel actuating gear on the shaft and means for locking said actuating gear to the shaft for movement in the opposite direction only.

In testimony whereof I affix my signature. 110

MAURICE FIGOUR.
